(No Model.)

F. M. SPEED.
PIPE MACHINE.

No. 503,102.

Patented Aug. 8, 1893.

UNITED STATES PATENT OFFICE.

FRANCIS M. SPEED, OF SAN FRANCISCO, CALIFORNIA.

PIPE-MACHINE.

SPECIFICATION forming part of Letters Patent No. 503,102, dated August 8, 1893.

Application filed August 2, 1892. Serial No. 441,939. (No model.)

To all whom it may concern:

Be it known that I, FRANCIS M. SPEED, a citizen of the United States, residing in the city and county of San Francisco, State of California, have invented an Improvement in 5 Pipe-Machines; and I hereby declare the following to be a full, clear, and exact description of the same.

My invention relates to that class of pipe-10 machines in which a flask confines a charge of plastic material, into which a core is forced whereby the material is molded within the flask about the core, to form the pipe. This class is exemplified by my Patent No. 437,871, dated October 7, 1890.

My invention consists in connection with an apparatus of this class of a movable plate within the base of the flask serving as a means for withdrawing the completed pipe.

It further consists in connection with said movable plate, of a rod extending therefrom through the flask, and serving the double purpose of providing for moving the plate, and as a guide for the core in its movement into 25 the flask.

It also consists in connection with said guide rod of a fixed guide within the core for further insuring the proper movement thereof.

In machines of this class it has been found 30 difficult to remove the pipe from the flask after it has been formed and properly set; and it is also of importance to accurately guide the core in the formation of the pipe.

The objects of my invention are to provide 35 simple and effective means for withdrawing the pipe from the flask and for accurately guiding the core.

Referring to the accompanying drawings for a more complete explanation of my invention,--Figure 1 is a vertical section of my machine or apparatus showing the material within the flask, and the core about to be forced down into it. Fig. 2 is an enlarged section of the same. Fig. 3 is a vertical section showing the core fully forced down into the material and the latter molded about it into the shape of the pipe. Fig. 4 is a cross section of the manufactured article.

A is the flask, secured at its lower end to a 40 suitable base B. The upper end is covered by a plate F having a central opening f, and removably secured by means of suitable studs

h and keys i. This covered plate is provided also with the vent openings g.

C is the core adapted to fit closely in the 55 central aperture f of the flask top, and to be forced down through said aperture, any suitable means being provided for effecting this movement. I have here indicated a presser K for this purpose.

The core C is concentric with the flask, and in order to guide it accurately in its movement therein it fits upon a guide rod D which rises centrally through the flask, its upper end passing through a suitable central hole 65 d in the bottom of the core. Additional accuracy of movement is insured by means of the interior perforated guide j fixed within the core which for this purpose is made hollow as shown, said guide being preferably of 70 a conical or funnel shape. Within the base of the flask is a plate E which may or may not form the bottom of said cylinder. It is best that it shall so form the bottom as shown. It rests upon the base support B and is movable within the flask. The guide rod D is secured to or formed with this plate. Upon the inner surface of the flask is seated removably a lining L of suitable material, the lower end of which rests upon the movable plate E. 80 This lining is for the purpose of preventing the material of which the pipe is formed from adhering to the flask; and, to insure its perfect operation in this respect, its meeting edges should overlap so that the material will 85 not come in contact with the flask. Around the exterior of the core is seated a suitable sheath M which prevents the material from adhering thereto.

The operation of the machine or apparatus 90 is as follows: The material from which the pipe is to be made, such for example, as asphaltum or some compound thereof, or other plastic material, is placed, while in a plastic condition in the flask, and in such quantity 95 that the displacement due to the entrance therein of the core will cause it to more than fill the annular space between said core when fully seated and the inner wall of the flask, the surplus passing out through the vent apertures g, the escape, however, being sufficiently difficult to provide for the necessary compression or molding of the material about the core. The amount of this material is sub-

stantially shown in Fig. 1 and the result of forcing the core down into it is shown in Fig. 3. In the movement of the core into the flask, the former is accurately guided by the rod D, this accuracy being further insured by the guide piece j. When the material is set, and the core is removed, the pipe is withdrawn from the flask by forcing upwardly the plate E which carries the pipe and the flask lining L out through the top of the flask, the cover F of which has been previously removed. Though this movement of the plate E may be effected in any suitable manner, the means here shown are preferable, namely, by suitable power applied to the rod D which is connected with the plate. By raising said rod the plate will be lifted and the pipe will be drawn out from the flask. It will thus be seen that the rod D serves the double purpose of a guide for the core, and of a simple means for operating the plate E to withdraw the formed pipe.

Having thus described my invention, what I claim as new, and desire to secure by Letters Patent, is—

1. In a pipe-machine having a molding flask and a core operating axially, to compress and mold plastic material therein, a rod in the flask upon which the core is guided, substantially as herein described.
2. In a pipe-machine having a molding flask and a core operating axially to compress and mold plastic material therein, a rod in the flask upon which the core is guided, and an interior fixed guide within said core fitting over the rod, substantially as herein described.
3. In a pipe-machine having a molding flask and a core operating axially, to compress and

mold plastic material therein, a movable plate in the base of the flask and a rod secured to said plate and passing through the flask, said rod forming both a guide for the core and a means for moving the plate to withdraw the pipe, substantially as herein described.

4. A pipe-making machine consisting of the molding flask having the removable cover with vents, the reciprocating core operating through said cover into the flask, the movable plate in the base of the flask, the rod rising therefrom and passing through the base of the core, and the fixed guide within the core operating over the rod, substantially as herein described.

5. A pipe machine having a flask closed at the bottom and open at the top and having a removable flask top provided with a central aperture to receive the core; the removable plate arranged within the flask on the base of the flask and provided with an upwardly projecting guide rod extending to the top of the flask and adapted for withdrawing the plate and the molded pipe from the flask, and the core provided in its bottom with a suitable central hole to receive such rod, and provided within the core intermediate its length with a perforated guide of a conical or funnel shape arranged to receive and engage such guide rod to center the core within the flask when the core is forced downward into the flask.

In witness whereof I have hereunto set my hand.

FRANCIS M. SPEED.
